UNITED STATES PATENT OFFICE.

CHRISTINA CATREVAS, OF BROOKLYN, NEW YORK.

BOOK-THEATER.

1,179,163.

Specification of Letters Patent. Patented Apr. 11, 1916.

Application filed December 27, 1915. Serial No. 68,671.

To all whom it may concern:

Be it known that I, CHRISTINA CATREVAS, a citizen of the United States, residing at Brooklyn, in the county of Kings and State 5 of New York, have invented certain new and useful Improvements in Book-Theaters, of which the following is a specification.

This invention relates to toy theaters and particularly to those made in knock-down 10 book form. It contemplates such structure of the book and contents whereby the main parts of the theater in folded form serve as covers for the book and constitute a portfolio or container for all other parts including 15 scenery characters costumes and the book of the play.

The invention therefore consists in the structure of parts and in their association, combination and arrangement substantially 20 as hereinafter set forth and claimed.

In the accompanying drawings which 25 form a part of this specification Figure 1 shows the theater book or book theater in the compact folded form of non-use; Fig. 2 illustrates the book theater opened and all 30 removable parts taken out save the "book of the play"; Fig. 3 is a plan of the theater floor or stage; Fig. 4 is a perspective of the theater set up; Fig. 5 shows one of the 35 beams for joining the proscenium to the back; Fig. 6 shows such beam folded along the longitudinal medial score and ready to be put into place; Figs. 7 and 8 show wings and Fig. 9 a back-drop for use in the im- 40 proved theater.

In the drawings 10 indicates the proscenium which forms the front cover of the book and 11 the base or foundation of the theater which serves as the back cover of 45 the book. The back of the theater 13 is hinged in any suitable way to the inside of the back cover as by a tab 14 of the same material as 13 glued to the cover, a score or the like having been made at 14' between tab and theater back to allow the latter to be folded down toward the hinge of the book Fig. 1. This hinge is indicated at 12 and consists of binders linen applied in the usual manner in forming backs of books.

To hold the front and back walls of the theater in raised position, Fig. 4, suitable 50 beams 15 similar to those disclosed in my Patent No. 1,107,757 of Aug. 18, 1914, are provided. These and the parts of the theater already described are preferably made 55 of cardboard. The beams consist of strips

scored longitudinally through the middle as at 15' so that they may be folded upon themselves when put into place. The ends of the beams are notched and when inserted 60 in holes 16 in the proscenium and holes 17 and notches 18 in the back 13 the beam notches engage the proscenium and the back and hold said parts in proper position.

A raised floor or stage is preferably provided the better to facilitate the setting of scenery with its downwardly extending tenons. Such floor is indicated by 19. It is provided with a front tab 20, back tab 21 and side tabs 22 to be folded downward 70 along scored lines 22' for stiffening the floor at its edges. The back tab is also of such width as to rest upon the foundation 11 and support the rear of the floor. The side tabs also have ledges or lugs 23 cut therefrom which remain in the same plane as the floor and project sufficiently to rest upon the floor beams 15. Obviously the front and side tabs of the floor may be made as wide as the back tab but by making them as described the floor with tabs unfolded lies 75 within the confines of the covers 10 and 11 when the book is folded and allows the area of the book to be somewhat restricted.

Holes 24 are cut in the floor to receive 80 the tenons 25 formed on the lower ends of wings 26 back-drop 27 and such other scenery as may be provided with the different plays to be put on. The parts of the scenery also have notched shoulders 28 for 85 engagement with the upper beams 15. These features of the scenery are set forth in detail in the patent above mentioned and are here shown with only sufficient fullness to 90 clearly disclose the present invention.

The "book of the play" indicated at 29 is 95 of a size such that it may be inclosed in the covers and preferably tied to the back 12 by a cord or ribbon 30 the title showing through the proscenium. The characters 100 and costumes will preferably be printed in sheets in a manner well known and the sheets inserted in the book between the folded-down back 13 and the book of the play or otherwise located therein as desired. The scenery will also be printed in 105 sheets and similarly inserted. The scenery, the characters and the costumes are to be cut out by the children in setting up the theater and putting on the play. The characters will be constructed or mounted in 110 any suitable manner for placement and

movement about the stage and some or all may be provided with removable costumes in forms well known in "paper dolls".

The covers 10 and 11 may be decorated as desired, 10 being preferably made to simulate the typical proscenium by having foot light, columns and the like represented thereon.

The invention claimed is:

- 10 1. A book theater having a foundation and proscenium hinged together to form covers of a book, a theater back hinged at its lower edge to said foundation, notched beams for engaging said proscenium and back at their upper and lower edges to hold them perpendicularly to said foundation, and a floor or stage for insertion between the proscenium the back and the floor beams.
- 15 2. A toy theater having a foundation and a proscenium and a back mounted thereon, floor beams connecting the proscenium and
- 20

back, and a stage having turned-down flaps on its edges for the purpose set forth and also having lugs at its sides cut from the side flaps for resting upon the floor beams. 25

3. A book theater consisting of a proscenium and foundation forming the covers thereof, a theater back hinged to the inside of the foundation and foldable inwardly thereon, removable beams for holding the 30 proscenium and the back perpendicularly to the foundation, a removable floor insertible between the proscenium and back and constructed to rest in part upon said beams, and a book of the play provided with means 35 for securing it in the covers so that the title thereof may show through the proscenium, substantially as and for the purpose set forth.

In testimony whereof I have affixed my 40 signature.

CHRISTINA CATREVAS.
